UNITED STATES PATENT OFFICE.

WILLIAM HENRY PLEASANTS, OF VICTOR, COLORADO, ASSIGNOR OF
ONE-HALF TO PERRY J. WEIPPER, OF SAME PLACE.

DESIGN FOR A MINER'S CANDLESTICK.

SPECIFICATION forming part of Design No. 30,406, dated March 28, 1899.

Application filed March 1, 1899. Serial No. 707,409. Term of patent 14 years.

To all whom it may concern:

Be it known that I, WILLIAM HENRY PLEASANTS, of Victor, in the county of El Paso and State of Colorado, have invented and produced a new and original Design for a Miner's Candlestick, of which the following is a full, clear, and exact description.

Reference is to be had to the accompanying drawing, forming a part of this specification, in which the figure is a perspective view of a miner's candlestick embodying my new design.

The design in its entirety consists of an elongated pointed shank *a*, having a loop *b* at the handle end, a plurality of spiral convolutions *c*, appearing at one side of the shank adjacent to the loop, and a hook *d*, appearing at the opposite side, the shank of the hook

rising substantially vertically. Extending transversely from the convolutions *c* is a transverse member *e*, which has a return-bend *f* and joins the lower end of the shank *d*.

The essential feature of the design consists of the candlestick having a shank and presenting spiral convolutions at one side, at the other side a hook rising substantially vertically, and a transverse member emanating from the convolutions and having a return-bend that joins the shank of the hook.

I claim—

The design for a miner's candlestick herein shown and described.

WILLIAM HENRY PLEASANTS.
